APPARATUS FOR CAPSULATING LIQUIDS

Walter McClure, Alma, Mich., assignor to Liquifoil Corporation, Alma, Mich., a corporation of Michigan

Application June 2, 1952, Serial No. 291,361

9 Claims. (Cl. 53—86)

This invention relates to new and useful improvements in apparatus for capsulating materials and particularly materials of liquid or pasty consistency.

It is often desirable to package small amounts or single applications of materials. For example, it has been found convenient to prepare hand lotion in small, individual packets for both advertising samples and retail sale. In use, the material is squeezed from the packet and the wrapper is then discarded. Also, it has been found convenient to similarly package comestibles such as mustard and the like for individual use in applications such as picnic kits, air-line lunches, and take-away hamburger or hot-dog concessions. Other uses of the above concept will readily suggest themselves.

An important object of the present invention is to provide an apparatus for making small, individual capsules or packets of materials such as the ones named specifically above.

Another object of the invention is to provide an apparatus of the above-mentioned character that is essentially rapid in operation and that produces the packets economically at a high rate of speed.

Still another object of the invention is to provide an apparatus of the above-mentioned character that produces a fluidtight and airtight packet which keeps the contents thereof essentially fresh for a relatively long time.

Yet another object of the invention is to provide an apparatus of the above-mentioned character that is substantially automatic in operation.

Other objects and advantages of the invention will be apparent during the course of the following description.

In the drawings forming a part of this specification and wherein like numerals are employed to designate like parts throughout the same:

Fig. 1 is a perspective view of a capsulating apparatus embodying the invention;

Fig. 2 is a transverse sectional view taken on the line 2—2 of Fig. 1;

Fig. 3 is a fragmentary sectional view taken on the line 3—3 of Fig. 2;

Fig. 4 is a fragmentary, elevational view of the portion of Fig. 1 designated by the arrow 4;

Fig. 5 is a fragmentary view between the forming dies of the apparatus as indicated by the line 5—5 in Fig. 1;

Fig. 6 is a fragmentary view showing a single capsule or packet of the type produced by the apparatus;

Fig. 7 is an enlarged, fragmentary, vertical sectional view taken on the line 7—7 of Fig. 1, particularly illustrating one of several identical valves which control operation of the apparatus;

Fig. 8 is a transverse sectional view taken on the line 8—8 of Fig. 2;

Fig. 9 is a fragmentary, vertical sectional view taken on the line 9—9 of Fig. 5;

Fig. 10 is a perspective view showing one of the die members used to form and seal the packet;

Fig. 11 is a view similar to Fig. 2 but showing the parts in elevation and illustrating the relationship thereof with adjacent parts of the apparatus; and

Fig. 12 is a diagrammatic view illustrating the pneumatic circuit which operates the various working parts of the apparatus.

In the drawings, wherein for the purpose of illustration is shown a preferred embodiment of the invention, the numeral 20 designates an upright support disposed at

the front of the machine 22. Mounted on one side of the support 20 adjacent the upper end thereof are inner and outer die members 24 and 26 carried by back-up plates 28 and 30 respectively. The back-up plates 28 and 30 are larger than dies 24 and 26, and the inner back-up plate 28 is fastened solidly to the support 20. Bolts 32 and 34 extend rearwardly through the back-up plates 28 and 30 at opposite sides of the die members 24 and 26. As perhaps best shown in Fig. 1, the bolts 32 and 34 extend rearwardly of the support 20 and the rearward ends thereof are connected by a crosshead 36 disposed transversely of and actuated by a fluid motor 38 mounted on the support 20 directly behind the die members 24 and 26. Springs 40 carried by the bolts 32 and 34 and confined between back-up plates 28 and 30 normally urge the latter apart so as to separate the die members.

The dies 24 and 26 are arranged opposite each other and have flat confronting surfaces each formed with medianly disposed upper and lower cavities 42 and 44. The two cavities 42 and 44 are vertically aligned and are separated by an intervening bridging portion 46. The upper cavity 42 extends through the upper end of the die, and the lower cavity 44 extends through the lower end thereof. Also it will be observed that the upper cavity 42 is relatively longer than the lower cavity 44 and in any event is sufficiently long to accommodate the entire capsule of material to be formed by the apparatus. The entire confronting surface of each die contiguous to the cavities 42 and 44 is corrugated as at 48, and the corrugations of the two die members interfit when the dies are brought together.

Mounted on the support 20 above the die members 24 and 26 is an ejection nozzle device comprising an ejection tube 50 carried by and extending downwardly from a suitable crosshead slide 52 which extends between and is slidably supported by guides 54 and 56 at opposite ends thereof. The upper ends of guides 54 and 56 are connected by a transverse member 58, and the entire ejection tube and slide assembly is attached to the support 20 by a pair of arms 60 and 62. As best shown in Figs. 1 and 4, the arms 60 and 62 embrace the support 20 and are securely fastened thereto by bolts 64. The arms extend forwardly of support 20 and between guides 54 and 56 and the terminal portions thereof are suitably fastened to the guides by bolts 66. A fluid motor 68 surmounting and suitably fastened to the transverse member 58 has a downwardly extending piston rod 70 which extends through member 58 and is fastened securely to the crosshead guide 52. Manifestly, operation of the fluid motor 68 causes the guide 52 and consequently the ejection tube 50 to reciprocate vertically.

The arms 60 and 62 also extend rearwardly of the support 20 and form part of a supporting structure 72, which carries spaced rolls 74 and 76 of paper, foil, or the like from which the packets are made. Strip material from the lower roll 74 extends forwardly over a suitable guide roll 78 journaled to and extending between suitable standards 80 and 82 fastened to and at opposite sides of the support 20. Strip material from the upper roll 76 similarly extends forwardly over a guide roll 84 journaled to and disposed between upright standards 86 and 88 fastened to and extending upwardly from the arms 60 and 62. The two pieces of strip material extend downwardly from the respective guide rolls 78 and 84, on opposite sides of the ejection tube 50, and between the die members 24 and 26.

Mounted on the support 20 below die members 24 and 26 is a suitable intermittent pulling mechanism comprising inner and outer jaws 90 and 92. The inner jaw 90 is mounted for vertical sliding movement between ways 94 and 96 defined by plates 98 and 100 respectively fastened to opposite sides of the support 20. The outer jaw 92 is disposed within a generally U-shaped, forwardly extending frame 102 carried by and movable with the rearward jaw 90. A pair of laterally spaced fluid motors 104 and 106 carried by the frame 102 and fastened to the jaw are operative to move the latter to and from the stationary jaw 90. Springs 108 and 110 also interposed between and fastened to the jaw

92 and frame 102 hold the jaws 90 and 92 normally separated. The strip material from rolls 74 and 76 extends downwardly from die members 24 and 26 between the jaws 90 and 92.

Vertical reciprocation of the pulling mechanism is achieved by a crank arm 112 fastened at one end to the stationary jaw 90 at the rearward side thereof and at the other end to an eccentric 114 fixed on and rotatably driven by the drive shaft 116 of a motor 118. As shown in Fig. 1, the drive shaft 116 is relatively long and extends entirely through an elongated housing 120 interposed between the support 20 and the motor 118. It will be readily apparent that the motor 118 acts through the drive shaft 116 to rotate the eccentric 114 and that the latter in turn acts through the crank arm 112 to move the clamping assembly vertically between the ways 94 and 96.

Material to be packaged by the apparatus is kept in a suitable container 122 (Fig. 11), and this material is delivered to the ejector tube 50 in successive, measured, uniform amounts. To this end, the material is forced constantly into a riser tube 124 in any suitable manner as by means of a pump 126 submerged in the material and connected to the bottom of the tube. From the tube 124 the material flows through a conduit 128 to an ejector loader valve 130 and thence into an ejector loader cylinder 132.

The valve 130 has a generally cylindrical casing 134 provided with a conical recess 136 at one end and a central passage 138 extending from the bottom of the recess to the opposite end 140 thereof. Mounted for rotation in the conical recess 136 is a correspondingly shaped valve body 142, and the latter has an inward extension 144 which projects into and is snugly received by the passage 138. A headed screw 146 extends axially through the valve body 142, and the projecting end of the screw carries a nut 148 which bears against a washer 150 disposed across the end of passage 138 (Fig. 2). The outer end of valve body 142 is centrally recessed as at 152, and a spring 154 confined between the bottom of the recess and the head of screw 146 holds the valve body 142 pressed against the wall of recess 136. Two separate longitudinal passages 156 and 158 in the valve body open through the inner tapered surface thereof and are separately registerable with a longitudinal passage 160 in the valve casing 134. Conduit 128 is connected to the valve body 142 in communication with passage 156 by a suitable coupling 162, and the valve casing is connected to the ejector cylinder 132 by a suitable union 164. As shown in Fig. 2 the union 164 is threaded into passage 160 and effects communication between the passage and the interior of the ejector cylinder 132. Passage 158, on the other hand, is connected at the outer end thereof by a suitable coupling 166 to a conduit 168 which extends to and is connected with the ejector tube 50 by a coupling 170.

The ejector cylinder 132 comprises a cylindrical body 172 having an internal cylindrical chamber 174 which communicates with passage 160 through the union 164 in the manner hereinabove described and which slidably receives a piston 176. As perhaps best shown in Fig. 2, the cylinder body 172 is fixedly mounted in the vertical wall 178 of housing 120, and the piston 176 is formed with an extension 180 which carries a follower 182 (Fig. 11). An eccentric cam 184 on drive shaft 116 is arranged for peripheral engagement with the follower 182, and this cam drives the piston 176 into the cylinder 174 once for each revolution of the drive shaft.

As suggested, the valve body 142 can be rotatably positioned to bring either of passages 156 and 158 into register with the passage 160. When the valve body 142 is positioned with passage 156 in register with passage 160, the container 122 is in direct communication with the cylinder 174, and pressure exerted by pump 126 forces material from the container 122 into the cylinder 174 each time the lobe of cam 184 rotates away from the follower 182. Thus, under these conditions the portion of cylinder 174 not occupied by piston 176 is filled with the material from container 122. If, at this time, valve body 142 is rotated to bring passage 158 into register with passage 160, communication between container 122 and cylinder 174 is cut off and the cylinder is brought into direct communication with the conduit 168 which connects with the ejector tube 50. When the lobe of cam 184 is rotated against follower 182 under these condi-

tions, the piston 176 is driven into cylinder 174 to force a limited predetermined amount of the material being packaged into and from the ejector tube 50.

Manifestly, if the above operations are properly timed, a predetermined uniform quantity of material is discharged from the tube 50 each time the apparatus operates in the manner described above. It will be apparent that the amount of material discharged from the tube 50 is determined by the size of cylinder 174 and that the charge can be selectively varied within limits by regulating the stroke of piston 176.

It will be apparent also that the valve body 142 must press against the case 134 with sufficient force to withstand pressure created at the interface of these two bodies by the pump 126 and by ejector cylinder 132. This function is performed by the spring 154 and it will be readily apparent that the pressure exerted by this spring can be selectively controlled by tightening or loosening the nut 148. In practice it is desirable to tension spring 154 sufficiently to prevent the material being forced out of the ejector loader valve 130 between the case 134 and the valve body 142, but the force exerted by spring 154 should not be substantially greater than the force required to achieve this end in order to facilitate rotation of the valve body 142 and to minimize wear and consequential galling of the relatively movable parts.

According to the present invention, the valve body 142 is rotatably actuated by a fluid motor 186 having a cylinder 188 carried by and rockable about a horizontal pivot 190 fixed to a vertical support 192 fastened to the frame of the machine at any suitable or convenient location (Fig. 8). A piston (not shown) is mounted for reciprocation in the cylinder 188, and the piston is provided with the usual piston rod 192 which extends from the cylinder and is pivotally attached as at 194 to an arm 196 fastened to and extending radially from the valve body 142.

In Fig. 8, the fluid motor 186 is shown with the piston retracted in the cylinder 190 to position the ejector valve 130 as shown by full lines with the passage 156 in register with passage 160. When fluid under pressure is admitted into cylinder 188 behind the piston to advance the latter in the cylinder, arm 196 is moved to the broken-line position in Fig. 8, and the valve body 142 is rotated to bring passage 158 into register with passage 160. Manifestly, the valve body 142 can be easily moved back and forth between these two positions, as indicated by the arrow in Fig. 8, merely by directing fluid under pressure to the cylinder 188 at one side or the other of the piston therein.

All the fluid motors 38, 68, 104, 106, and 186 are actuated in proper timed relation by eccentric cams 198, 200, and 202 fixed to and rotatable with the drive shaft 116 and by valves 204, 206, and 208 coactive with and actuated by respective cams. The valves 204, 206, and 208 are here shown mounted in a block 210 on and integral with the housing 120 directly above the cams 198, 200, and 202. The three valves 204, 206, and 208 are identical in construction and operation, and a detailed description of only one therefore is given.

Each valve comprises a plunger 212 mounted for reciprocation in a sleeve 214 which is press-fitted or otherwise fixedly secured in a bore 216 extending upwardly from the bottom of block 210 (Fig. 7). Vertically spaced inlet passages 218 and 220 are provided in the block 210, and these passages align with correspondingly positioned outlet passages 222 and 224 in the opposite side of the block. The two inlet passages 218 and 220 register with correspondingly spaced inlet ports 226 and 228 provided in the sleeve 214, and the two outlet passages 222 and 224 register with correspondingly spaced outlet ports 230 and 232 in the sleeve. The plunger 212 is formed with a diametrical through passage 234 which is movable by reciprocation of the plunger selectively into register with either of the ports 226, 230, or 228, 232. An L-shaped passage 236 provided in the plunger 212 above passage 234 registers at one end with outlet port 230 when the passage 234 is in register with the ports 228 and 232. The opposite end of passage 236 opens through the top of the plunger. Also provided in the plunger 212 below the through passage 234 is an L-shaped passage 238, and one end of the latter passage registers with the outlet port 232 when passage 234 is in register with ports 226 and 230. The opposite end of L-shaped passage 238 opens

through the bottom of the plunger. In this connection it will be observed that the plunger 214 extends downwardly from the block 210, and a cam follower 240 rotatably mounted on the lower end of the plunger engages the operating cam of the valve. Fig. 7 shows a vertical sectional view through the middle valve 206, and the cam follower 240 of this valve rests upon cam 200 (Fig. 1). Each valve also includes a cap 242 which is threaded into an opening 244 provided in the block 210 centrally of and above the valve plunger 212. As shown in Fig. 7, the opening 244 communicates with the open end of plunger 212 and the surrounding sleeve 214, and a spring 246 confined between the upper end of the plunger and the upper end of the cap normally urges the plunger downwardly to assure constant engagement of the cam follower 240 with the eccentric cam which operates the valve.

The apparatus here shown is operated by air under pressure but it will be readily appreciated that it could just as well be operated hydraulically. As shown in Fig. 12, air under pressure is carried to the machine by an air line 248. Air is carried to valve 204 through a branch line 250, and the end of the latter has bifurcations 252 and 254 which connect with the two inlet passages 218 and 220 respectively. Similarly, air under pressure is carried to valve 206 by a branch line 256, and the end of this line is provided with bifurcations 258 and 260 which connect with respective inlet passages 218 and 220 of the valve. In the same manner, air is carried to valve 208 by a branch line 262 having terminal bifurcations 264 and 266 which connect with respective inlet passages 218 and 220 of the valve.

The upper discharge passage 222 of valve 204 is connected to fluid motor 186 ahead of the piston therein by a conduit 268, and the lower discharge passage 224 of the valve is connected to the same motor behind the piston by a conduit 270. Fig. 12 shows cam 198 positioned to lift valve 204 so as to connect the conduits 250 and 268 to retract the piston in cylinder 186 and to position the ejector valve 130 as shown in Figs. 2 and 8. At this time the cylinder of fluid motor 186 behind the piston is vented to atmosphere through conduit 270 and the L-shaped passage 238.

The upper discharge port 230 of valve 206 is connected by a conduit 272 to the cylinder of fluid motor 68 ahead of the piston therein, and the lower discharge passage 224 is connected by conduit 274 to the cylinder of motor 68 behind the piston. In Fig. 12, the valve 206 is shown raised to connect conduits 256 and 272 so as to retract the piston in cylinder 68 and to hold the ejector nozzle 50 raised.

The lower discharge port 224 of valve 208 is connected by conduits 276 and 278 to fluid motor 38 behind the piston therein to close the dies 24 and 26 and by conduits 280 and 282 to fluid motors 104 and 106 ahead of the pistons therein to open the clamping jaws 90 and 92. The upper discharge port 222 of valve 208 is connected by conduits 284 and 286 to fluid motor 38 behind the piston therein to open the dies 24 and 26 and by conduits 284, 288, and 290 to the cylinders of fluid motors 104 and 106 behind the pistons therein to close the jaws 90 and 92.

The operation of the device is now described, and for this purpose it will be assumed that the ejector loader 130 is positioned as shown in Fig. 2, permitting material being packaged to be charged to the ejector cylinder 132, and it will be further assumed that the lobe of cam 184 is rotating away from the follower 182 so that the material forced under pressure into the ejector cylinder 132 moves the piston 176 to the left so as to introduce a full charge into the ejector cylinder. Also, it will be assumed that the ejector tube 50 is raised, that the dies 24 and 26 are open, and that the clamping jaws 90 and 92 are closed. In this position of the clamping jaws, the eccentric pivot of cam 114 is at the upper limit of its travel preparatory to lowering the puller unit of which the jaws 90 and 92 are a part. Also, it will be assumed that the strips 74 and 76 extend downwardly from guide rolls 78 and 84 respectively on opposite sides of the ejector tube 50, between the dies 24 and 26, and thence downwardly between the clamping jaws 90 and 92. In the position described above, the strips are gripped tightly between clamping jaws 90 and 92, and since the puller assembly is being moved downwardly by the eccentric cam 114 the strips are being pulled downwardly past the ejector tube 50 and between the open dies 24 and 26.

Shortly before the ejector loader cylinder 132 is completely filled, cam 200 moves away from the follower 240 of valve 206 sufficiently so that the valve spring 246 moves the valve to the position shown in Fig. 7 and permits air under pressure to enter fluid motor 68 behind the piston therein. Immediately when this occurs, the ejector tube 50 moves downwardly.

Almost immediately after the ejector tube 50 begins to descend, cam 202 releases valve 208 sufficiently so that the latter assumes the position shown in Fig. 7. Immediately when this occurs, air under pressure is admitted into fluid motor 38 behind the piston therein to close dies 24 and 26 and simultaneously into motors 104 and 106 ahead of the pistons therein to open clamping jaws 90 and 92.

As soon as clamping jaws 90 and 92 open they release the paper strips 74 and 76 which then remain stationary in the machine. As suggested, the ejector tube 50 extends into the upper cavities 42 of the dies 24 and 26 when in fully lowered position. Preferably the tube extends almost but not quite to the bottom of the cavities. The timing is such that the dies 24 and 26 close after the ejector tube 50 is fully lowered. As the dies come together, they form the strips 74 and 76 around the portion of tube 50 within cavities 42 and simultaneously clamp the portions of the strips adjacent to the cavity. In this connection it will be observed that the interfitting corrugations 48 of the dies crimp the entire area of the strips disposed between the corrugated portions of the dies. Preferably, the dies are slightly wider than the strips so that the entire area thereof not disposed within cavities 42 is crimped. If the strips 74 and 76 are of a material such as metallic foil or the like the crimping action and pressure imposed by the die members 24 and 26 alone seals the strips together sufficiently to form a fluidtight pocket around the tube 50. On the other hand, if the strips 74 and 76 are made of some other material such as paper or plastic film, it may be necessary to pre-coat the confronting faces of the strips with a suitable adhesive, and indeed it may be desirable under certain circumstances to coat strips of metallic foil with adhesive. In this latter event, it is desirable to heat the dies 24 and 26 electrically or by circulating a heated liquid therethrough in any suitable or conventional manner so that the dies soften the adhesive when they are brought into clamping engagement with the strips 74 and 76 and thus effect an efficient fluidtight adhesive bond between the strips. Any of a number of well-known vinyl resins can be used which have the necessary adhesive characteristics and which are sufficiently inert to the material being packaged. Closing the dies 24 and 26 only after the ejector tube 50 is fully lowered prevents the tube from tearing the strips 74 and 76 when the pocket is formed therein.

Immediately after the pocket is formed, cam 198 moves away from valve 204 permitting the latter to move to the position shown in Fig. 7 so that air under pressure is admitted to fluid motor 186 behind the piston therein. This action moves the ejector loader valve to the broken-line position in Fig. 8 and interconnects the ejector cylinder 132 with the ejector tube 50.

Shortly after the occurrence of this contingency, cam 200 lifts valve 206 so that air under pressure is admitted to fluid motor 68 ahead of the piston. This action causes the ejector tube to rise out of the pocket previously formed in strips 74 and 76 and to a position above the forming dies 24 and 26.

Substantially simultaneously with the operation of valve 206, cam 184 pushes against follower 182 to advance piston 176 in the ejector cylinder 132, and as the piston advances it forces material previously charged to the cylinder through the ejector loader valve 130 and conduit 168 to the ejector tube 50. Thus, the material is ejected from tube 50 as the latter is raised from the pocket. The charge ejected by tube 50 preferably substantially completely fills the pocket within the die cavities 42.

During the above phase of the operation the eccentric cam 114 rotates to raise the puller assembly. It will be recalled, however, that the clamping jaws 90 and 92 are open at this time so that the unit is raised without effect on strips 74 and 76.

As the ejector tube 50 approaches the upper limit of its travel, cam 202 again operates valve 208 to operate the fluid motor 38 so as to open dies 24 and 26 and

simultaneously to operate fluid motors 104 and 106 so as to close the clamping jaws 90 and 92. As these two operations occur simultaneously, the dies 24 and 26 are open by the time the clamping jaws 90 and 92 are fully closed, and the arrangement is such that the clamping jaws close when the puller unit has been raised to the upper limit of its travel.

Also, after the material has been charged to ejector tube 50, cam 198 again lifts valve 204 so that the latter connects the air pressure with fluid motor 186 ahead of the piston therein. This action returns the ejector loader valve to the position shown in Fig. 2 and connects the ejector loader cylinder 132 with the container 122 preparatory to retraction of the piston 176. At about the time the dies 24 and 26 open and clamping jaws 90 and 92 close, cam 184 releases piston 176 so that another charge of material is introduced into the cylinder 174.

The cam 114 then begins to move the puller unit downwardly; and since clamping jaws 90 and 92 are together at this time, they pull strips 74 and 76 downwardly between the open dies 24 and 26.

This completes the cycle of operation.

In connection with the foregoing it should perhaps be pointed out that the puller unit 160 moves the strips 74 and 76 downwardly step by step each time a distance sufficient to bring the upper portion of the previously filled pocket into alignment with the lower cavities 44 of die members 24 and 26. Thus, when the die members 24 and 26 come together during any cycle of operation except the first in any series of operations, they close and seal the pocket which was formed and filled by the prior operation and before charge of material is ejected from the tube 50. Fig. 5 illustrates the manner in which a pocket is formed in the strips 74 and 76 around the ejector tube 50 and how the previously formed pocket is closed simultaneously by the dies 24 and 26.

As a result of successive operations as described above a series of discrete small blisters or packets are formed between the strips 74 and 76. Fig. 6 illustrates one of the blisters or packets so formed. Each packet comprises a separate container of the material being packaged. Any suitable number of these packets may be folded together or, if desired, they may be separated either automatically by a conventional cutting mechanism (not shown) incorporated as a part of the machine or subsequently either manually or automatically in any suitable or conventional manner.

It is, of course, desirable that the machine operate as rapidly as possible and speeds in the order of one hundred cycles per minute have been achieved. In order to operate at such high speeds, it is necessary to accelerate the speed of ejector nozzle 50 as it approaches the upper limit of its travel in order to break or snap off the jet of material being discharged therefrom. This is particularly true in the case of a relatively viscid or pasty substance. If the material is not snapped off abruptly in this manner the strips 74 and 76 moving downwardly on opposite sides of the nozzle 50 tend to pull material therefrom, resulting in faulty charging and creating a generally messy condition which may affect the sealing of the packets by the dies 24 and 26. According to the present invention breaking off of the fluid stream from the nozzle 50 is accomplished by the particular valve construction which controls the ejector nozzle actuator 68. By providing a cam-operated valve of the type here disclosed, air is admitted to the fluid motor 68 gradually as the passage 234 moves into register with ports 226 and 230. Manifestly, a relatively small amount of air will be admitted to the ejector nozzle immediately when passage 234 begins to register with the aligned ports; and, as the passage moves more and more into register, increasing amounts of air are admitted to the fluid motor 68. Thus, initial upward movement of the ejector nozzle 50 is relatively slow and the rate of travel is progressively increased as it moves upwardly. Maximum acceleration is achieved as the nozzle approaches the upper movement of its travel and this change in acceleration produces the desired result described above.

Also, the use of a valve 206 to control the reciprocatory movements of the ejector nozzle 50 contributes important advantages to the operation as it provides necessary dwell periods at opposite ends of the reciprocatory travel. A dwell period when the ejector nozzle 50 is at the lower

limit of its travel assures that the tube 50 is all the way down before the dies 24 and 26 are completely closed, and, as described above, this prevents the ejector tube from breaking through the strip material 74 and 76. The dwell period at the upper limit of travel allows the liquid material in the nozzle to stabilize itself and assures a uniform feed. It will be readily appreciated in this connection that an absolute uniform feed is essential to make the machine commercially practicable.

Also, in order to achieve maximum efficiency in operation it is necessary that the dies 24 and 26 be closed essentially rapidly and open relatively slowly. In addition, it is necessary that the gripping jaws 90 and 92 close essentially slowly and open relatively rapidly. This operation is achieved in a particularly efficient manner by the valve 208 which controls the fluid motors 38, 104, and 106. Rapid closing of the dies 24 and 26 and rapid opening of clamping jaws 90 and 92 are achieved because the pressure of air in passage 234 when it is in register with ports 226 and 230 tends to hold the plunger 212 raised. Thus as the cam 200 begins to rotate downwardly, it moves away from the follower 240, and there is only the pressure of spring 246 to shift the plunger to the lower position. This spring 246 is sufficiently strong, however, to gradually overcome the resistance offered by the air. Initial downward movement of the plunger is slow, but as passage 234 moves gradually out of register with ports 226 and 230 the resistance offered by the air pressure decreases and the rate of travel of the plunger increases. By the time passage 234 moves out of register with ports 226 and 230 resistance of the air column is reduced to zero and the spring 246 is able to complete the downward travel with a rush. Thus passage 234 moves into register with ports 228 and 232 substantially instantaneously and air is admitted equally quickly and in large volume into fluid motors 38, 104, and 106 to close dies 24 and 26 and open jaws 90 and 92 rapidly. On the other hand, relatively slow opening of the dies and relatively slow closing of the clamping jaws 90 and 92 is achieved by the same valve construction. Upward movement of the plunger 212 is resisted at all times by the spring 246 but the resistance of the spring is overcome by the cam 202. However, the rate of travel of the plunger 212 is controlled entirely by the peripheral contour of the cam 202, and the plunger cannot rise any faster than the cam pushes it. Thus, passage 234 moves progressively and relatively gradually into register with ports 226 and 230. As a consequence, air is at first admitted gradually and in small amounts to fluid motors 38, 104, and 106. However, the volume of air gradually increases as passage 234 moves progressively into register with ports 226 and 230. As pressure builds up in the motors 38, 104, and 106 the dies open and the jaws close; but because of the gradual nature of the pressure buildup the respective opening and closing movements of the dies and jaws are relatively slow.

It is a feature of this invention that the dies 24 and 26 and clamping jaws 90 and 92 are operated by a single control, viz., valve 208. This particular arrangement assures that these two mechanisms never get out of synchronism.

It will be readily appreciated that, while the machine here illustrated has only one ejector tube 50, it may be equipped with any desired number of tubes by increasing the capacity of the ejector cylinder 132 or by providing two or more ejector cylinders which operate in unison. Also it is of course necessary to provide the dies 24 and 26 with as many cavities as there are ejector tubes.

Having thus described the invention, I claim:

1. Apparatus for encapsulating liquids comprising a vertically movable ejector tube, opposed relatively movable die members arranged on opposite sides of said tube, the inner confronting sides of said die members having interfitting corrugations and also having aligned cavities into which the lowered tube extends, means for drawing strips of sheet material downwardly in intermittent operations on opposite sides of said tube and between said die members, means for bringing the die members into clamping engagement with said sheet material while said tube is lowered whereby to form the sheet material around the tube and to crimp the surrounding portion of said material to provide a liquid tight pocket containing the tube, means for raising the tube out of the pocket thus formed

and simultaneously discharging a measured amount of liquid into said pocket, means for separating said die members after the tube is raised, and means for pulling said strips downwardly when said die members are separated to position the upper portions of said pocket above the level of liquid therein between the lower portions of said die members whereby the pocket is closed and sealed by the next operation of said die members.

2. The combination as set forth in claim 1 including means for gradually accelerating movement of the ejector tube as it is withdrawn from said cavity whereby maximum speed is attained at the end of the withdrawal movement.

3. The combination as set forth in claim 2 including means for holding the ejector tube still at least momentarily at the end of its travel away from said die members.

4. The combination as set forth in claim 1 including means for bringing the ejector tube to the end of its movement into the cavity before the die members are brought entirely together and for holding the tube in this position at least momentarily after the die members have closed.

5. The combination as set forth in claim 1 including means for bringing said die members together relatively quickly and for separating said die members relatively slowly.

6. The combination as set forth in claim 5 wherein the means for moving said die members comprises a fluid motor operatively connected to said die members, valve means for controlling flow of operating fluid to said motor, a rotatably driven cam coactive with said valve means to position the same for admitting fluid to the motor to separate said die members, and spring means coactive with

said valve to position the same for admitting fluid to the motor to bring said die members together.

7. The combination as set forth in claim 1 wherein the means for advancing said strips of sheet material comprises grippers at opposite sides of and movable into and out of engagement with said sheet material and including means for bringing said grippers into engagement with said sheet material as said die members are separated and for moving said grippers out of engagement with said sheet material as said die members are brought together.

8. The combination as set forth in claim 7 including means for moving said grippers relatively slowly into engagement with said sheet material and for moving said grippers out of engagement with said sheet material relatively rapidly.

9. The combination as set forth in claim 8 wherein said gripper-actuating means comprises a fluid motor operatively connected to said grippers, a valve for controlling flow of operating fluid to said motor, rotatably driven cam means coactive with said valve to position the same for admitting fluid to said motor to move the grippers into engagement with said sheet material, and spring means coactive with the valve to position the same for directing fluid to the motor to move the grippers out of engagement with said sheet material.
